UNITED STATES PATENT OFFICE

RICHARD ELSSNER AND RALPH H. CARTER, OF JOHNSON CITY, TENNESSEE, ASSIGNEES
TO AMERICAN GLANZSTOFF CORPORATION, OF NEW YORK, N. Y., A CORPORATION
OF DELAWARE

HERMETIC CONTAINER

Application filed September 4, 1931. Serial No. 561,120.

Our present invention has to do with a new and novel container for a spool of yarn.

One object of our invention is to produce a container within which yarn wound upon spools may be dried so that even shrinkage results.

Another object of our invention is to provide such a container that the drying of the yarn is so controlled that the drying will always take place in some specified direction.

Other objects will become apparent from a reading of the following specification, and a study of the attached drawing, in which:

Figure 1 is a longitudinal cross-sectional view of our new container in place upon a spool containing yarn, and

Figure 2 is a cross section of the spool and container.

In the manufacture of artificial filaments, 20 yarn, threads, etc., by any of the well-known processes wherein the filaments, etc. are "wet-spun", they are collected directly upon perforated spools on a so-called spinning machine. These spools, after the necessary wet- 25 treatment (deacidifying, desulphurizing, etc.), are dried. This drying is accomplished by placing the spools upon carrying means, and transporting them into a drier. Here, air is circulated at some velocity, and 30 usually at a relatively high temperature, so that the outside and the inside of the spools tend to dry at the same time. Thus the yarn cake or body, which is wound upon the perforated spool, dries from both directions to- 35 wards the middle. This results in a yarn body which is perfectly dried, on the outside and inside, but imperfectly dried in the middle. The resulting yarn has a very uneven shrinkage. This uneven shrinkage has 40 an objectionable effect on the qualities of the yarn, and effects, for example, the even dry- ing of the same.

Through the use of our new container, however, it is possible to obtain an even 45 shrinkage of the yarn body, and corresponding desirable characteristics resulting therefrom.

As shown in the drawing, the new container is used in conjunction with a per- 50 forated spool 1 upon which the wet yarn

body 2 is wound. The container proper 3 has a cover portion 4. Gaskets 5, 5 are provided, which act to hermetically seal the container against the spool. This container may be made of any rigid material which will not be acted upon by the liquids with which the yarn body is wet. These materials may be, for example, bakelite, stainless steel, aluminum, hard rubber, etc. The cover 4 is equipped with a gasket 7, which completes 60 the seal. The cover 4 is provided with an orifice 8 terminating in inwardly projecting rims which act to position the covers upon the spool ends. The inwardly projecting rims 9, 9 may be of such a length that they 65 will guide the spool of yarn into the containers without allowing the delicate yarn to come in direct contact with the container.

In operation, the yarn is wound upon the perforated spools in the customary manner, 70 and the container placed therearound. After the covers are sealed in place by means of the gaskets, the spool, in the container, is placed in the drying room in the ordinary manner. Because the outside of the spool 75 is sealed, the circulation of air is through the interior of the spool only, and, as a result, the inside of the yarn body dries first. Thus all the moisture in the yarn body is removed through the inside of the spool. The spools 80 are then uncovered and placed on a twisting machine where the filaments or yarn is wound loosely upon a similar spool, and twisted. In this way, the yarn formerly on the outside is now on the inside. The resulting body 85 is rewet, the spools are again placed in the containers, and the same drying operation repeated. As a result a yarn with a very even shrinkage results.

Although some departures may be made 90 from the exact structure disclosed, the fundamental operations of the container and gasketed covers sealed with the gaskets against the spool should be maintained.

What we claim is:

1. In a container, in combination, a cylindrical wall portion, an inturned projection at one end thereof, a gasket associated with the said projection, a cover portion, said cover portion being open-centered and chan- 100

- nel-shaped, and adapted to engage the other end of the cylindrical wall portion forming a fluid tight seal therewith.
- 5 2. A container and closure therefore comprising a cylindrical container wall inturned and upturned to form a containing means, and an open-centered channel-like closure adapted to form a fluid tight seal with the top end of said container.
- 10 3. In combination, a cylindrical wall, in-turned and upturned portions at the bottom end thereof, a gasket at the junction of the inturned and upturned portions, a beaded edge at the top of the said cylindrical portion, and a closure, comprising a flat strip, the inner side being downturned and the outer in-and down turned, a gasket on the inside of the downturned portion and on the outside of the said in-and downturned portion.
- 15 20 4. In combination, a container and closure therefor, and a spool to be held therein, comprising a cylindrical wall inturned and up-turned to form a containing means, and holding one end of the spool, and an open-centered channel like closure adapted to form a fluid tight seal with the other end of the spool and the top of the container.
- 25 30 5. In combination, a container and closure therefor, and a spool to be held therein, said spool having wound thereupon a body of thread, comprising a cylindrical wall positioned so that no contact is made with said body of thread, and which is inturned and upturned to form a containing means, and holding one end of the spool, and an open-centered channel like closure adapted to form a fluid tight seal with the other end of the spool and the top of the container.
- 35 40 45 6. In combination, a spool with filaments wound thereon, and a container comprising a rigid wall portion spaced from the surface of the filaments, a projection at one end of the said wall portion adapted to form a fluid tight seal with one end of the spool, and a closure portion adapted to close the upper end of the container between the other end of the spool and wall portion, forming a fluid-tight seal with both elements.
- 50 60 In testimony whereof we affix our signatures.

RICHARD ELSSNER.
RALPH H. CARTER.
